UNITED STATES PATENT OFFICE.

CHARLES WAGENFÖHR, OF BROOKLYN, NEW YORK.

DESIGN FOR A BRUSH OR MIRROR BACK, &c.

SPECIFICATION forming part of Design No. 21,018, dated August 25, 1891.

Application filed July 3, 1891. Serial No. 398,436. Term of patent 14 years.

To all whom it may concern:

Be it known that I, CHARLES WAGENFÖHR, a citizen of the United States, residing at Brooklyn, in the county of Kings and State of New York, have invented and produced a new and original Design for Brush and Mirror Backs and Handles, of which the following is a specification, reference being had to the accompanying drawings, forming a part thereof.

10 In the accompanying drawings I have represented my design.

My design is oval or pear shaped in contour, and the central portion thereof, which is substantially plain and without ornamentation, is 15 also oval in shape, it being separated from the border by a depression, said depression being covered at certain points by the overlapping of the flower design of the border. The border is ornamented at four nearly equidistant points

20 by raised conventional scroll-line figures which are represented as binding and securing the border, and against one of the said scrolls the upper portion of the foliated head of the twisted handle abuts, the said scroll

25 appearing to rest upon the said foliated head as upon the capital of a pillar. The scroll at the top has a scalloped or shell ornamentation, which projects beyond the contour of the mirror-back and forms a finish for the top thereof. The border is ornamented with a

30 of the oval, then passes upwardly on each side in a curved line around the border, and then through the curve of the scroll at the top and ends on one side in a pendent cluster of curving conventional leaves and a conventional flower or fruit. A similar cluster of curving conventional leaves surrounding a conventional flower or fruit is placed at each of two points on the opposite side of the oval, one 35 being near the apex of the oval and the other near the opposite portion thereof, while the vine-stem on that side is branched. The whole figure is preferably raised, and the handle has the greater portion of the length thereof 40 twisted design, with a foliated head or capital at the point of the union of the handle with the body of the back, the scroll at the apex of the oval of the back resting lightly on the said capital or foliated head. 45

I claim—

1. The design for a brush or mirror back and handle, substantially as shown.
2. The design for a brush or mirror back, substantially as shown. 55
3. The design for a handle for a brush and mirror, substantially as shown.

CHARLES WAGENFÖHR.
